Attorney.

UNITED STATES PATENT OFFICE.

PETER SARTORY, OF BAYSWATER, LONDON, ENGLAND.

HAIR CURLER AND WAVER.

Original application filed February 1, 1922, Serial No. 533,360, and in Great Britain February 3, 1921.
 Divided and this application filed April 26, 1926. Serial No. 104,823.

This invention relates to hair curling and waving appliances such as are used in processes of permanently waving natural hair, and this application is a division of 5 my copending application for hair curlers and wavers, filed February 1, 1922, Serial No. 533,360.

Curling and waving appliances of the kind used in the art to which the present invention relates, usually comprise a sleeve or mandrel rotatably mounted upon a relatively fixed member that projects beyond the root end of the mandrel, such projecting end being tied with string or the like to a tress 10 of natural hair close to the scalp, after which the hair tress is coiled about the mandrel and secured at the tip end thereof; the coiled hair tress being subsequently tightened upon the mandrel by turning the mandrel 15 relatively to the fixed member.

The operation of tying the root end of a curler to a tress of natural hair is difficult and tedious, the tying having to be effected as near to the roots as possible, while great 20 care and dexterity is required to efficiently tie the hair tress to the curler without inconvenience or injury to the patient.

Further, when the curler is secured to a hair tress by tying with string or the like, 25 this latter is apt to slip or break under the severe stresses imposed when the coiled hair tress is tightened upon the sleeve or mandrel, and so occasions considerable inconvenience to the patient and delay in the 30 operation of curling and waving the hair.

The main object of the present invention is to eliminate tying the tress by hand to the root end of the curler.

Another object is to achieve securing the 40 tress to the root end of the curler mechanically by means operable from the tip end of the curler.

A further object is to facilitate generally 45 the operation of securing the curler close up to the root end of a hair tress without risk of injury or marking the hair.

In accordance with the present invention 50 a curler is provided with mechanical means for rapidly and efficiently securing the curler close up to the root end of a hair

tress, thus dispensing with the operation of tying and the risks and disadvantages incidental thereto.

In the accompanying drawings is illustrated by way of example a preferred form 55 of the invention as applied to curlers comprising a mandrel including a plurality of independently rotatable sections as described in my co-pending patent application Serial No. 533,360.

Fig. 1 is a side view of the curler, and Fig. 2 a perspective view on an enlarged scale of the root end of the curler, while Fig. 3 is a sectional view of the tip end thereof also to an enlarged scale to more 65 clearly show details of construction.

Referring to the drawings: the curling and waving appliance is shown to include a composite mandrel that comprises a root end section 1 and an opposite or tip end section 2, between which are arranged intermediate sections 3, the sections all being freely carried for independent rotation on a tubular axis member 4 comprising at the root end a part protruding beyond the section 1 and formed as a cross-piece 5 bored as indicated at 6 and 7 for the reception of the shank 8 and point 9 of a hook 10 formed at the end of an axial rod 11 extending through the 70 mandrel.

At the tip end the axis member 4 is internally threaded for the reception of a threaded sleeve 12 which itself takes over the threaded tip end of the rod 11. 13 indicates a squared lug for a key, if required. 75

From the foregoing description it will be observed that the cross-piece 5 forms the fixed jaw, and the hook 10 the movable jaw of a clamping device controlled and operable from the tip end of the curler by rotating the sleeve 12, the selective rotation of which determining the selective adjustment of the hook 10 to the cross-piece 5.

In operation the sleeve 12 is rotated so as to thrust the hook away from the cross-piece 5 until the point 9 of the hook has emerged from the bore 6 in the cross-piece, thereby opening the clamping loop formed between the part 10 and the cross-piece. The curler 80 is then moved over the tress so as to engage 100

the latter within the loop near the root of the tress, the loop then being closed by reversely rotating the sleeve 12 until in fact the tress is actually clamped to the curler.

5 Thereon curling is effected as described in co-pending patent application No. 533,360.

Alternatively, a screwed flexible member such as a Bowden wire may be substituted for the rigid hook member including the 10 parts 10 and 11 just referred to, one end of the wire being secured to the cross-piece and the other to the screw or nut such as 13 beyond the sleeve 12.

15 The external thread of the sleeve 12 may be of coarser pitch than its internal thread, and of opposite hand so as to obtain a quick adjustment of the hook to the cross-piece.

Further, it should be noted that the length of the rod 11 may be less than the mandrel, 20 in which case the sleeve 12 will be lengthened or disposed suitably nearer the root end of the axis member, the sleeve could then be turned by a suitable key if not readily accessible for hand turning.

25 14 is a clamping ring which embraces the tip section 2 which is a split section and is provided with an adjusting screw 15. By tightening the clamp 14 the split section 2 is locked as firmly as required to the axis member 4 so that the section 2 can be turned in either direction by the application of sufficient torque, the object of which construction is fully described in the aforesaid co-pending patent application No. 533,360.

35 I claim:—

1. In a hair curler and waver including a rotatable mandrel and a relatively fixed member protruding from the root end of the mandrel, the combination with said protruding end of the fixed member of a clamping member, a control disposed at the tip end of the curler, and connecting means between the control and clamping member extending through said mandrel, operation of said control effecting movement of the clamping member to co-operate with said protruding end whereby the root end of a tress of hair disposed between them is secured to the curler.

40 2. In a hair curler and waver including a rotatable mandrel and a relatively fixed member protruding from the root end of the mandrel, the combination with said protruding end of the fixed member of a clamping member, a rotatable control disposed in the tip end of the mandrel, and connecting means between the control and clamping member extending through said mandrel, operation of said control effecting drawing of the clamping member on to said fixed member whereby the root end of a tress of hair disposed between them is secured to the curler.

45 3. In a hair curler and waver including a rotatable mandrel and a relatively fixed axis

member, the combination with said member of a clamping device arranged at the root end of the axis member, a control therefor disposed at the tip end of the curler, and connecting means between the control and clamping device extending through said mandrel.

4. In a hair curler and waver, the combination with a rotatable mandrel and a relatively fixed axis member, of a clamping device of which the fixed jaw is on the root end of the axis member, a control for operating the movable jaw of the device, disposed at the tip end of the curler, and connecting means between the control and said movable jaw extending through said mandrel.

5. In a hair curler and waver including a rotatable mandrel and a relatively fixed axis member, the combination with the axis member of a cross-piece formed thereon at the root end forming the fixed jaw of the clamping device and a movable jaw operable to and from the cross-piece, a rod extending from said movable jaw through the axis 90 member to the tip end of the curler, a threaded sleeve taking over the rod at the tip end and engaging within the axis member at the tip end of the mandrel whereby selective rotation of said sleeve controls movement of 95 the movable jaw relatively to the fixed jaw.

6. In a hair curler and waver including a rotatable mandrel and a relatively fixed axis member, the combination with the axis member of a cross-piece bored parallel to the axis 100 of the curler and also coincident therewith, a rigid hook including a shank extending through said axial bore of the cross-piece and through the axis member to the tip end of the curler, the point of the hook being 105 adapted to enter the said bore parallel to the curler axis, and rotatable means at the tip end of the curler to reciprocate said shank so as to open the loop formed between said hook and cross-piece where the point of the hook engages in the respective bore therein or to retract the hook so clamping a tress disposed within the loop therebetween.

7. In a hair curler and waver including a rotatable mandrel and a relatively fixed axis 115 member, the combination with the axis member of a cross-piece bored parallel to the axis of the curler and also coincident therewith, a rigid hook including a shank extending through said axial bore of the cross-piece 120 and through the axis member to the tip end of the curler, the point of the hook being adapted to enter the said bore parallel to the curler axis, and externally threaded sleeve mounted in the tip end of said axis member and also in threaded engagement with the hook shank extending therethrough which the relative positions of hook to cross-piece 125 may be adjusted by selectively rotating said sleeve.

8. In a hair curler and waver including a rotatable mandrel and a relatively fixed member protruding from the root end of the mandrel, the combination with the fixed member of mechanical means for securing the root end of a tress thereto, and control means for operating said mechanical secur-
- ing means disposed at the tip end of the curler and connected to the mechanical means by means extending through the mandrel.

In testimony whereof I affix my signature.

PETER SARTORY.
